UNITED STATES PATENT OFFICE.

JAMES CAVANAGH, OF BOSTON, MASSACHUSETTS, ASSIGNOR TO UNITED SHOE MACHINERY CORPORATION, OF PATERSON, NEW JERSEY, A CORPORATION OF NEW JERSEY.

TURN SHOE.

Application filed August 8, 1919. Serial No. 316,226.

To all whom it may concern:

Be it known that I, JAMES CAVANAGH, a citizen of the United States, residing at Boston, in the county of Suffolk and State 5 of Massachusetts, have invented certain new and useful Improvements in Turn Shoes; and I do hereby declare the following to be a full, clear, and exact description of the invention, such as will enable others skilled 10 in the art to which it appertains to make and use the same.

This invention relates to turn shoes the soles of which are provided with a reinforce for the sewing-rib to strengthen it.

15 The present prevailing style in shoemaking, particularly in the manufacture of turn shoes, requires a sole shaped with an extremely pointed toe, known to the trade as a "peaked-toe" sole. Shoes in which such soles are incorporated are extremely difficult 20 for the operative at the inseaming machine to handle because of the quick turn required, after the shoe has been inseamed on one side, in order to bring the other side of the shoe 25 in proper relation to the stitch forming instrumentalities. Inseaming machine operatives who are not highly skilled will start to swing the shoe too soon, with the result that the position of the sewing-rib adjacent the 30 tip of the toe will be turned from its proper position at right angles to the path of movement of the awl and needle. As a result the sewing-rib is pierced by the needle at an acute instead of a right angle, this angle 35 growing smaller and smaller, as the swinging continues, until the tip of the toe reaches the stitch forming point. Those skilled in the art will recognize that the effect of this 40 is to cause a material weakness of the sewing-rib such that the inseam is pulled through during the strain of turning the shoe. This crippling of the shoe may be remedied, according to the present invention, 45 by backing the sewing-rib with a strengthening material designed to hold the stitches in place under the strain of the turning operation. A material, the structure of which is efficient to this end, is the heavy canvas or duck which is ordinarily used in reinforcing 50 insoles, since the threads which extend transversely of the sewing-rib when the reinforce is in place, act as anchors to hold the inseam stitches from pulling through the weakened sewing-rib.

55 The object of the present invention is to

produce a turn shoe the sole of which is provided with an improved type of reinforce for the sewing-rib the construction and mode of application of which will be explained in the following specification. Accordingly the invention comprises a turn shoe with a reinforced sole having the novel characteristics hereinafter described and defined more particularly in the appended claims.

The preferred embodiment of the invention is illustrated in the accompanying drawing in which Figure 1 shows a plan view of a peaked-toe turn sole provided with the novel reinforce for the sewing-rib; Fig. 2 70 is a cross-section on the line 2-2 of Fig. 1; Fig. 3 is a modification; and Fig. 4 is a section on an enlarged scale through a portion of the finished shoe indicated by the line IV-IV in Fig. 3.

In the embodiment of the invention illustrated in the drawing the turn sole 3 is provided with the usual marginal shoulder 4, oblique channel 5, and channel flap 6 cut therefrom. This sole fitting may be obtained 80 by use of a turn channeling machine such as is disclosed in Letters Patent of the United States to Frederic E. Bertrand No. 1,030,704, dated June 25, 1912, the sole thereafter being passed through a turn sole molding machine, preferably of the type disclosed 85 in Letters Patent of the United States to Albert E. Johnson, No. 1,307,820, dated June 24, 1919, which will curl the channel outwardly over the between substance preparatory 90 to applying the reinforce. The reinforce comprises a textile fabric tape 7, preferably of heavy duck or canvas which is laid in the angle inside the sewing-rib and folded centrally to form two leaves which lie 95 both against the channel 5 and the inner surface of the channel flap 6. The tape is of such width that the edges of its leaves, after folding, lie approximately at the top of the flap and the inner edge of the channel. 100 The tape 7 is provided with cement on its attaching face which effects a close adhesion to the leather of the sole, and may be formed-in by any suitable machine for applying reinforce to soles.

105 After the sole and upper have been sewed together wrong side out in the usual way, the stitches of the sole-attaching seam passing through the between substance or through the sewing rib 6 substantially at its 110

base and through the reinforce 7, and after the surplus material at the margins of the upper and of the channel flap has been trimmed as usual, the shoe is turned right 5 side out, that is to say to bring the grain surface of the sole outward and its flesh surface on the inside of the shoe where it is engaged by the foot of the wearer. During this operation of turning the shoe the sole- 10 attaching seam is subjected to a severe strain, as already suggested, but the stitches are prevented from pulling through the sewing-rib by the reinforce 7. Furthermore, the channel flap will be turned back toward the 15 channel and pressed down as usual before or when the shoe is relasted and leveled so that the reinforce will be substantially concealed within the channel.

While the only portion of a good grade 20 peaked-toe sole that need be reinforced is the portion of the sewing-rib extending back a short distance from the tip at the toe end of the forepart, it will be apparent, from the succeeding discussion of the advantages 25 of the invention, that where the stock of the body-blank is inferior resulting in a weak sewing rib, an application of the reinforcing tape to the entire length of the sewing-rib will be advantageous since it increases the 30 strength of the weak rib to such an extent as to permit the inseaming operation to proceed without danger of crippling the sole. The length of tape required for good grade peaked-toe work is shown in Fig. 3.

35 It has heretofore been proposed to reinforce both turn soles and insoles, when inferior material is used for the body-blank, by the application of a sheet of reinforcing fabric extending over the entire forepart of 40 the sole. Such a turn sole is disclosed in Letters Patent of the United States to Albert E. Johnson No. 1,200,114, dated October 3, 1916. Several disadvantages which accrue 45 from this method of reinforcing are overcome by the present invention. Firstly, after forming-in the sheet of fabric into the channel at one side of the sole, the forming-in at the other side tends to pull 50 loose the margin of the fabric on the first side. This is due to the fact that the fabric is bent over the forming-in tool at such an acute angle that there is no chance for it to slip from its free margin, resulting in a 55 drag across the sole. This objection is entirely overcome by the use of a single layer of reinforce in the form of a tape which may, during its application to the sole, be freely drawn from either margin without 60 injury to the sole. Secondly, in inseaming a shoe provided with a sole reinforced by a sheet of fabric, the fabric will draw and tend to buckle the sole when stitching down the first side. This distortion of the sole 65 cannot take place when a reinforcing tape alone is employed. Thirdly, when a sheet

reinforced turn sole is wet to turn the shoe, the leather and the fabric absorb different amounts of moisture with the result that on drying, the sole buckles. It is therefore highly advantageous to keep the fabric surface at a minimum by the use of tape. Fourthly, the sole is in a mull temper when the shoe is inseamed and the use of a tape reinforce applied to the channel alone, will permit the sole to stretch and conform to 75 the last where a sheet reinforce will stiffen the sole to such an extent that this conforming to the last cannot take place effectively.

It has also been proposed heretofore, in the making of welt shoes, to feed an unce- 80 mented tape through the channel guide of a welt sewing machine during the inseaming operation. Such a method is disclosed in Letters Patent of the United States to Myron L. Keith No. 534,159, dated February 12, 85 1895. The difficulty encountered in using the Keith method is that in feeding in a flimsy narrow tape of fabric practically simultaneously with the formation of the stitches, the guide does not place the rein- 90 force well in the channel or always accurately in the channel so that the needle will pierce its center. This is due to the required formation of the guide to feed the tape in advance of its placement in the channel, and 95 to inaccuracies of channeling. As a result the welter does not always sew through the tape which results in a weakening of portions of the inseam and discomfort to the wearer of the shoe. This difficulty is wholly 100 overcome by use of the present sole in which the tape is placed or formed tightly and securely in the channel as a stock-fitting operation before the sole is assembled with the upper. The sole then has its tape reinforce 105 accurately placed and a strong sewing-rib is necessarily produced. There is an additional advantage in employing a tape rein- 110 force of this type in a turn, or single sole, shoe in that it furnishes the necessary 115 strength during the turning operation while it does not lessen the flexibility of the sole, which is one of the great advantages of a turn shoe, and moreover it is substantially concealed in the finished shoe as shown in Fig. 4, whether or not the shoe is provided 120 with a sock lining, and therefore does not impair its appearance.

The nature and scope of the invention having been indicated and the proposed embodiment of the invention having been specifically described, what is claimed as new, is:—

1. A turn shoe comprising, in combina- 125 tion, an upper and a single sole which has been sewed thereto with the sole and upper wrong side out and then turned right side out, the grain face of the sole being outward in the finished shoe and the flesh face being prepared with a continuous sewing-rib to 130

receive the seam securing the upper and sole together and being provided with a continuous reinforce cemented within the inner angle between the sewing-rib and the flesh face of the sole to receive the stitches of the seam and prevent them from pulling through the sewing-rib when the shoe is turned, the foot-engaging part of the flesh surface of the sole being free from the reinforce to preserve its flexibility and prevent impairment of the appearance of the inside of the shoe.

2. A turn shoe comprising, in combination, an upper and a single sole which has been secured thereto with the sole and upper

wrong side out and then turned right side out, the sole being provided with a sewing-rib and a channel on the face which is next the foot when the finished shoe is worn, a seam passing through the sewing-rib and the upper to secure the upper and sole together, and a textile reinforcing strip cemented to the inside of the sewing-rib and in the channel at the toe to hold the stitches of the seam and prevent them from pulling through when the shoe is turned, the flesh, or inner, surface of the sole being free from said strip in order to preserve its flexibility.

JAMES CAVANAGH.
